UNITED STATES PATENT OFFICE.

CHARLES E. BUNNER, OF GRAFTON, WEST VIRGINIA.

NATURAL-GAS BURNER.

972,056.

Specification of Letters Patent.

Patented Oct. 4, 1910.

Application filed June 10, 1910. Serial No. 566,210.

To all whom it may concern:

Be it known that I, CHARLES E. BUNNER, a citizen of the United States, residing at Grafton, in the county of Taylor and State 5 of West Virginia, have invented new and useful Improvements in Natural-Gas Burners, of which the following is a specification.

This invention relates to gas burners of that type which mixes the gas with air before the gas reaches the combustion chamber 10 of the furnace or boiler.

The invention has for its principal object to provide an improved air-regulating and mixing device for burners of this character so that complete combustion can be produced.

Another object of the invention is to improve and simplify the construction and operation of devices of this character so as to 20 be comparatively simple and inexpensive to manufacture, reliable and efficient in use, and readily manipulated.

With these objects in view and others, as will appear as the description proceeds, the 25 invention comprises the various novel features of construction and arrangement of parts which will be more fully described hereinafter and set forth with particularity in the claims appended hereto.

30 In the accompanying drawings, which illustrate one embodiment of the invention, Figure 1 is a perspective view of the device. Fig. 2 is a longitudinal section thereof. Fig. 3 is a view of the inlet end of the burner. Fig. 4 is a transverse section on line 4—4, Fig. 2.

Similar reference characters are employed to designate corresponding parts throughout the views.

40 Referring to the drawings, A designates the tubular body of the burner that has one end expanded into a flaring mouth 1 into which air is admitted. Over the mouth is a conical head 2 which is fastened by bolts 45 3 to the mouth end of the body A, and in this head are spiral air-admitting openings 4 which begin adjacent the apex of the head and terminate adjacent the base thereof, the said slots increasing in width progressively.

50 Fitted on and rotatable around this head is a conical valve 4' which has slots 5 corresponding to those of the head, so that by turning the valve, the slots thereof can totally or partially register with the openings 55 of the head to control the supply of air to the burner body A. The valve can be

clamped in adjusted position by means of a screw 6 which passes through an arcuate slot 7 in the valve and screws into the body A.

Extending longitudinally into the mouth end of the body A is a gas-conducting tube or pipe 8 which has intermediate its ends a threaded opening 9 to receive the end of a gas supply pipe 10 which passes through an opening 11 in the wall of the body at the mouth thereof where the said body is formed with a boss. This pipe is clamped in place by nuts 12, and is adapted to be connected with a suitable source of gas. 70 The pipe 8 terminates about midway of the body A so that between the end of the pipe and the discharge end of the body, a chamber 13 is provided in which the gas and air are effectively mixed before entering the 75 furnace. Extending longitudinally of the pipe 8, which projects out of the head 2 at the apex thereof, is a tubular stem 14 that has on its inner end a flaring head or deflector 15 that is frusto-conical so that the gas will be discharged into the chamber 13 in 80 the form of a hollow cone, and, by reason of this, it will intercept the current of air passing longitudinally of the body A and thoroughly mix therewith. Surrounding this 85 stem or pipe 14 is a spiral ridge 16 which fits the bore of the pipe 8 so that a helical passage 17 will be formed between the pipes 8 and 14 beginning at a point where the gas enters the pipe 8 and terminating at the deflector or gas distributor 15. The pipe 8 has an internal bevel 18 at the distributor so 90 as to be parallel with the outer surface of the latter. The pipe or stem 14 is adjustable longitudinally by means of a hand-turned 95 sleeve 19 which is internally threaded to engage the threads 20 on the outer end of the pipe or stem 14, the said pipe or stem passing through a stuffing box 21 on the outer end of the pipe 8, the said box being screwed on 100 the latter pipe, and the sleeve has a swivel connection with the stuffing box 21 so that the turning of the sleeve will cause longitudinal movement of the stem 14 to vary the outlet area for the gas between the deflector 15 and the conical seat 18. This pipe 14 is open from one end to the other, and on its outer end it is provided with an inlet cone or mouth piece 22 so that air can be drawn into and through the pipe by the injector 110 action of the gas discharged through the burner body. A burner of this character can

be correctly adjusted so as to proportion the supply of air to the gas for obtaining the best combustion, and the burner can be readily taken apart and assembled when required.

From the foregoing description, taken in connection with the accompanying drawings, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made when desired as are within the scope of the claims appended hereto.

Having thus described the invention, what I claim, is:—

1. A burner of the class described comprising a tubular body open at one end, a conical head on the inlet end of the body, said head having air inlet ports, a conical valve rotatably mounted on the head and having inlet ports adapted to be moved into or out of register with the ports of the head, a centrally-disposed longitudinally-extending pipe terminating within the said body, means for connecting the pipe with a source of gas, means for imparting a whirl to the gas while in the said pipe, and a deflector for distributing the gas into the air passing through the said body.

2. A burner comprising a tubular body having a flaring mouth or inlet end, a head fastened over the inlet end and having air inlet ports, means for opening and closing the said ports, a pipe extending longitudinally through the body and extending out of the head, a gas supply pipe extending transversely into the body at the inlet end thereof and secured to the first-mentioned pipe to supply gas thereto and to support the pipe rigidly in place, an element extending longitudinally through the first-mentioned pipe and of less diameter than the bore of the latter, means between the element and the surrounding pipe to form a spiral passage for the gas to pass into the burner, a deflector on the said element for distributing the gas outwardly toward the body of the burner, and means for discharging air axially into the said body.

3. A burner comprising a tubular body having a flaring mouth or inlet end, a head fastened over the inlet end and having air inlet ports, means for opening and closing the said ports, a pipe extending longitudinally through the body and extending out of the head, a gas supply pipe extending transversely into the body at the inlet end thereof and secured to the first-mentioned pipe to supply gas thereto and to support

the pipe rigidly in place, an element extending longitudinally through the first-mentioned pipe and of less diameter than the bore of the latter, means between the element and the surrounding pipe to form a spiral passage for the gas to pass into the burner, a deflector on the said element for distributing the gas outwardly toward the body of the burner, said element being hollow from one end to the other to admit air to the said body in the axial region thereof, and means for longitudinally adjusting the element to control the gas supply through the said passage.

4. A burner comprising a body open at one end to receive air and open at the opposite end to deliver a mixture of gas and air, a pipe extending longitudinally into the said body from the inlet end thereof and terminating short of the discharge end to provide an intermediate mixing chamber, a pipe extending longitudinally of the first-mentioned pipe and of less diameter than the latter, means between the pipes for forming a spiral passage, means for discharging gas through the said passage, a stuffing box on the first-mentioned pipe and through which the second-mentioned pipe extends, threads on the second-mentioned pipe, a sleeve engaging the threads, a swivel joint between the said sleeve and stuffing box to prevent longitudinal movement of the sleeve as the same is rotated to move the second pipe longitudinally, a deflector on the inner end of the said movable pipe coöperating with the inner end of the first-mentioned pipe to vary the effective outlet area for the gas, controllable means for admitting air to the burner body at a point behind the gas, and means for supplying air to the said mixing chamber through the second pipe.

5. A burner comprising a body open at one end to receive air and open at the opposite end to deliver a mixture of gas and air, a pipe extending longitudinally into the said body from the inlet end thereof and terminating short of the discharge end to provide an intermediate mixing chamber, a pipe extending longitudinally of the first-mentioned pipe and of less diameter than the latter, means between the pipes for forming a spiral passage, means for discharging gas through the said passage, a stuffing box on the first-mentioned pipe and through which the second-mentioned pipe extends, threads on the second-mentioned pipe, a sleeve engaging the threads, a swivel joint between the said sleeve and stuffing box to prevent longitudinal movement of the sleeve as the same is rotated to move the second pipe longitudinally, a deflector on the inner end of the said movable pipe coöperating with the inner end of the first-mentioned pipe to vary the effective outlet area for the gas, a conical head extending over the inlet end of

the body and having an opening at its vertex to receive the outer end of the first-mentioned pipe, said head having air inlet ports, a conical valve rotatably mounted on the head for opening and closing the said ports, and means on the outer end of the second-mentioned pipe for admitting air thereto.

In testimony whereof I affix my signature in presence of two witnesses.

CHARLES E. BUNNER.
